ADAPTER FOR RADIAL GRINDING ATTACHMENTS

Ernest Vidales, San Antonio, Tex.

Application August 31, 1949, Serial No. 113,423

1. Claim. (Cl. 51—216)

1 This invention relates to an adapter for supporting a radial grinding attachment of a tool grinder, and has for one of its objects the production of a simple and efficient means for supporting a radial grinding attachment for angular adjustment to tilt the radial grinding attachment to a desired angle relative to a conventional grinding wheel.

A further object of this invention is the production of a simple and efficient hinged adapter for a radial grinding attachment for facilitating the tilting of the radial grinding attachment at a selected angle and locking the adapter in a selected position.

Other objects and advantages of the present invention will appear throughout the following specification and claim.

In the drawings:

Figure 1 is a top plan view of the adapter;

Figure 2 is a perspective view of the adapter;

Figure 3 is an end elevational view of the adapter, portions of a conventional tool grinding apparatus being shown in dotted lines;

Figure 4 is a rear elevational view of the adapter, a portion thereof being shown in section on line 4—4 of Figure 1;

Figure 5 is a transverse sectional view taken on line 5—5 of Figure 1.

By referring to the drawings, it will be seen that 10 designates the rectangular base-plate of the adapter which may be anchored to the conventional supporting table of a tool grinder by means of suitable anchoring bolts 11. These bolts 11 which are conventional fit into the notches 13^a which are formed in the opposite ends of the base-plate 10 and are connected to the table T in the conventional manner.

The base-plate 10 may fit flat upon the table of certain types of tool grinders, such for instance, the Cincinnati Tool Grinder, in which event the raising blocks 13 may be removed or detached from the under face of the base-plate or section 10. The raising blocks 13 are removably held in position by the retaining dowel pins 9 and by abutment with the retaining lugs 8 which lugs 8 are secured to the under face of the base-plate or section 10 by means of the screws 14. The blocks 13 are provided with oppositely beveled ends 13^b to snugly fit the table of the type of machine such as the Brown and Sharp Tool Grinder and to permit the adapter to be rotated or reversed 180° to obtain a reverse tilt. The blocks 13 will raise the adapted base-plate 10 above the face of the table T in this instance. The blocks 13 are notched, as at 13^c to register with the

notches 10^a formed in the ends of the base-plate 10 to receive the anchoring bolts such as the bolts 11 shown in Figure 3.

It should be noted that this invention comprises the adapter itself and does not include the structure of the tool grinding mechanism, since the adapter is designed to be used in connection with various types of tool grinders and radial grinding attachments, radius, milling, forming and fly cutters. The device also is adapted for use on ball end mills when grinding clearances.

An upper rectangular work-supporting plate or section 15 is hinged, as at 16, to one side edge of the base-plate 10 and carries upstanding bolts 17 and 18, one being preferably located near each end of the plate 15. The bolts 17 and 18 are adapted to attach the conventional work support 19 to the upper face of the plate 15. Suitable apertures 20 and 21 also are formed in the plate 15 to receive retaining lugs of the conventional work support which may be mounted thereon.

Upstanding guide members 22 and 23 are secured to the front edge 24 of the base plate 10 by means of the longitudinal anchoring screws, such as the screw 25 shown in Figures 2, 3 and 5. The guide member 22 is provided with an arc slot 26, and the guide member 23 is provided with a similar arc slot 27 which is aligned with the slot 26 of the member 22. The member 22 is provided with suitable graduations 28 upon its outer face, and the member 23 is provided with similar graduations 29 upon its outer face, as shown in Figure 2.

Tightening screws 30 and 31 are carried by the opposite ends of the upper plate 15 near its forward edge 24 in a position to pass through the respective arc-shaped slots 26 and 27 respectively. The tightening screws 30 and 31 are preferably threaded into the plate 15, as shown in Figure 1, and these screws are provided with binding portions 32 and 33 respectively, which engage the upstanding guide members 22 and 23 to lock the upper plate 15 in a selected adjusted tilted position relative to the base-plate 10. Knurled knobs 34 and 35 are carried by the tightening screws 30 and 31, as shown. It will be noted that the guide members 22 and 23 have direct abutting and wiping engagement with the ends of the work supporting section 15.

From the foregoing description it should be understood that the present device is adapted to be applied to various types or makes of tool grinders without departing from the spirit of the invention. By using a cup wheel the cutting edge can be ground to a proper angle to protect the

cutting edge against chipping, and it also gives a longer tool life between grinds. When using a cup-shaped wheel to grind a side milling cutter to a radius form, the tilt of the upper plate 15 is adjusted to the desired angle for the first and second relief of the cutter.

Certain detail changes may be made in the detail structure herein set forth without departing from the spirit of the invention, so long as these changes fall within the scope of the appended claim.

Having described the invention, what I claim as new is:

An adapter of the class described comprising a base section, a work supporting section hinged to said base section along one side edge thereof, graduated upstanding slotted arc-shaped guide members carried by the base section at the ends thereof, said guide members being curved rearwardly and having direct abutting and wiping engagement with the ends of the work supporting section, tightening screws directly threaded into the ends of said work supporting section itself and passing through the slotted guide members, said screws overlapping the slots of the guide members for frictionally binding the guide members against the ends of the work supporting section to frictionally lock the work supporting section at

a selected angle relative to the base section upon the guide members, upstanding work support engaging bolts carried by said work supporting section, said work supporting section having retaining lug receiving apertures formed therein intermediate the work support engaging bolts, said base section having anchoring bolt receiving apertures at the ends thereof, raising blocks secured to the under face of the base section and having apertures registering with the anchoring bolt receiving apertures, the raising blocks having oppositely beveled ends to snugly fit the table of a selected type of grinder, and dowel pins removably securing the raising blocks to the base section.
